CURT K. WANNINGER AND HERBERT HOFMANN, OF BRONXVILLE, NEW YORK.

BELT BUCKLE.

Application filed May 26, 1927. Serial No. 194,484.

This invention relates to belt buckles or belt fastening elements and in particular to a type which is adjustable to fit the body of the wearer and to provide a slight adjustment or take-up during the use thereof.

A particular object of the invention is to provide a simplified belt buckle construction which is neat in appearance, which prevents slipping of the belt, which prevents wearing of the belt at its ends and which renders the operation of fastening the belt practically instantaneous.

A further particular object of the invention is to provide a belt buckle or fastening element which not only protects the end of the belt but also protects the clothing of the wearer as well as giving strength to the belt construction and preventing relative slippage of the belt end.

To enable others skilled in the art to fully comprehend the underlying features of our invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in perspective of our improved belt buckle construction, the same being shown in connection with a belt.

Figure 2 is a view in rear elevation of the belt buckle construction shown in Figure 1, the same being shown as it would appear looking from the inside of the belt.

Figure 3 is a view in section taken on the line 3—3 of Figure 2 and shows the construction of the buckle parts and their relative relation when secured together.

Figure 4 is a view showing the end of the belt that is adapted to receive the eye-plate.

Figure 5 is a view in perspective of the eye-plate which is adapted to be secured to the end of the belt illustrated in Figure 4, and

Figure 6 is a view in perspective of the rear side of the hook plate which is arranged to be secured in any one of the openings of the opposite end of the belt from that shown in Figure 4.

Referring to the drawings in detail, 5 indicates a belt of the usual flexible construction and which is made of leather or other tough material and which is adapted to encompass the body of the wearer to retain trousers or other garments in position.

It has been a problem heretofore to effect-

tively secure the ends of a belt together to prevent the relative slipping thereof when the parts of the belt buckle become worn as when the friction clasp type buckle is used, 60 the continued gripping of the belt causes the same to become smooth in one portion with the result that it slips when in use and does not properly perform its function.

In our invention we have overcome this 65 objection by positively securing the ends of the belt together not only at one point but providing for an adjustment so that the ends of the belt may be moved longitudinally relatively to each other.

On one end of the belt which, when in position overlies the opposite ends and which is designated by the numeral 6, we have provided the usual openings 7 spaced in any suitable manner to receive a hook 8 which is 75 formed integrally with and on the under side of a hook plate 9, the outer face 10 of which may be suitably engraved or ornamented with the initials of the wearer. The hook plate 9 may be provided with the side flanges 10 80 which guide the belt in the hook plate, the flanges 10 being connected by the bridge or connecting piece 11 which is arranged at one end of the hook plate and is adapted to overlie the belt 5. It is of course understood that 85 some means must be provided for securing the hook plate to the belt so that no bulge may occur in the latter and while I have shown a solid bridge 11, joining the ends of the flanges 10, it is to be understood that 90 the flanges 10 might be dispensed with and lips turned over on any portion of the hook plate 9 to encompass the edges of the belt to secure the hook plate thereto. It is quite evident that the hook plate may be placed in 95 any position on the end 6 of the belt and the hook 8 thereof pass through any of the openings 7 in the belt end so that the hook plate is thereby adjusted longitudinally of the end 6 of the belt.

In order to retain the hook plate or the ends of the belt locked together, we have provided on the opposite end 12 of the belt 5, an eye plate 13. This eye plate is made of metal as is of course, also the hook plate and is doubled to provide an eye portion 14 and a rear protective portion 15, the front edge thereof, or where the metal is turned, as at 16, being adapted to protect the edge 17 of the belt end 12 to prevent that portion from 110 fraying and to enhance the appearance thereof. The end of the belt 12 is provided with

a rivet opening 18 and an elongated slot portion 19, the opening 18 being arranged to coincide with the opening 20 provided in the rear edge of the eye plate 13, the eye plate being secured to the belt end through the medium of a suitable rivet like eyelet 21 which passes through the opening 20 in the eye plate and opening 18 in the belt end 12. When the eye plate 13 has been positioned as described, the eye slot or opening 22 formed in the eye portion 14 of the eye plate 13 are in alignment with the opening 19 in the belt end 12 and it will be quite evident that the openings 22 provide an adjustable feature by reason of the fact that the hook 8 of the hook plate 9 can be secured in either one of the eyes 22 to provide for the necessary take-up after the hook plate is positioned at the proper opening 7 in the end 6 of the belt 5.

20 The eye plate may be fancifully shaped as shown in Figure 5 to provide an ornamental appearance and it may be engraved or suitably decorated to enhance the appearance of the belt as a whole.

25 It is quite evident from inspection of Figure 3 that when the hook plate is connected to the eye plate by reason of the fact that the hook 8 is disposed within the eye plate 13, that the protective backing 15 of the eye plate will prevent the hook 8 from coming into contact with the clothing of the wearer, thus providing an effective shield and dispensing with any projection on the back of the belt which would constantly rub against the clothing at the point where the buckle was continuously used.

It is evident, therefore, that we have provided a belt fastening means, the hook plate portion of which can be adjusted longitudinally of the end of the belt and which can then be secured in a suitable eye plate which will prevent contact of the catching means with the clothing.

It is also evident that we have provided a fastening means which does not need continuous adjustment and which presents an ornamental appearance and conceals the fact that a hook is used to hold both ends of the belt together.

50 It is evident also, that we have provided a belt buckle of simplified construction, which does not require constant manipulation or adjustment to properly position the same in order to attain the circumferential size of the belt desired.

While we have illustrated and described our invention with some degree of particularity, we realize that in practice various alterations therein may be made. We therefore 60 reserve the right and privilege of changing the form of the details of construction or otherwise altering the arrangement of the correlated parts without departing from the spirit of the invention or the scope of the appended claims.

Having thus described our invention what we claim as new and desire to secure by United States Letters Patent is:—

1. The combination with one end of a belt having an elongated opening therein, of a doubled eye plate fitting over the end of the belt and secured thereto, the plate having elongated openings in one side thereof arranged to correspond with the belt end opening, a buckle on the opposite end of the belt and a hook on the buckle arranged to selectively engage the eye plate openings. 70

2. The combination with one end of a belt having an opening therein, of a doubled eye plate arranged about the end of a belt and secured thereto, the plate having openings in one face thereof corresponding with the belt opening, a buckle on the opposite end of the belt, a hook on the buckle arranged to selectively engage the eye plate openings and the opposite side of the eye plate constituting a covering for the end of the hook whereby it will not catch the clothing of the wearer. 80

3. The combination with a belt, one end of which is provided with an elongated opening, of an eye plate doubled to fit over said end of the belt and having an opening in the outer face thereof coinciding with the opening in the belt end, a buckle on the other end of the belt, a hook on the buckle adapted to enter 95 the eye plate opening to releasably secure the eye plate and buckle together and the under face of the eye plate constituting a covering for the end of the hook whereby it will not catch the clothing of the wearer. 100

4. The combination with a belt of a U-shaped eye plate arranged to be positioned over and secured to one end of the belt and having an opening in one face thereof and a hook plate carried on the other end of the 105 belt a hook thereon arranged to engage the opening in said eye plate, and a belt bridging strip on said hook plate.

5. The combination with a belt having an opening in one end thereof, of an eye plate 110 bent to provide front and back faces and arranged to be positioned over said end of the belt to conceal the same and having an opening in the front face thereof, the plate opening coinciding with said belt end opening, a hook plate carried on the other end of the 115 belt and a hook thereon arranged to engage the opening in said eye plate.

6. The combination with a belt, one end thereof having an elongated opening therein, of an eye plate bent to provide front and back faces and arranged to be positioned over said end of the belt to conceal the same and having a plurality of elongated openings in the front face thereof arranged to coincide with the opening in the belt end, a hook plate carried on the other end of the belt, a hook thereon arranged to selectively engage the 125 openings in the eye plate and the back face of the eye plate being arranged to prevent 130

contact of the hook with the clothing of the wearer.

7. The combination with a belt, one end of which is provided with an elongated opening, 5 of an eye plate bent to provide front and back faces and arranged to be positioned over said end of the belt to conceal the same, means for securing the eye plate to the belt, the eye plate having openings in the front face thereof 10 arranged to coincide with said belt end open-

ing, a buckle carried on the other end of the belt, a hook thereon arranged to selectively engage the openings in said eye plate and the back face of the eye plate being arranged to prevent contact of the hook with the clothing 15 of the wearer.

In testimony whereof we affix our signatures.
